UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 3, 1925. Serial No. 34,542.

This invention relates to typewriter collating devices in which work-sheets are superposed in various relations preparatory to typing thereon. It may be especially useful 5 for typing statements where several separate statements are required to be copied or recorded on a single ledger sheet, so that a succeeding entry is typed on the same quickly and without waste of space.

10 According to the present invention, a collating table having side gages and one or more paper-holding clips mounted at each side is supported on arms pivoted to the carriage-frame of a typewriter, and is connected with the feed-roll-release mechanism of said typewriter through one of said pivoted arms, so that the feed-rolls are thrown off the platen, and the paper-holding clips are closed when the collating table is swung forward 15 about its pivot to collating position. Also the feed-rolls are thrown on the platen again, and the clips are opened when the collating table is swung to its rearmost position.

20 25 To use the collating table, it is swung forward to collating position, and the statement and the ledger-sheets, with a carbon-sheet between them, may be inserted together from the rear of the platen in the usual way. The ledger-sheet lying next to the platen may be 30 first positioned on the collating table in such a way that its last entry will come one line space above the printing line of the platen. When the ledger-sheet is registered, it may 35 be held securely in place by the right-hand clip and lateral gage until the statement-sheet and the carbon-sheet have been positioned together and clipped. Then by simply swinging the collating table rearwardly 40 about its pivot, the feed-rolls are thrown up against the platen thereby gripping the statement and ledger sheets in the usual way. The feed-roll movement is completed just before the clips are automatically released 45 or opened at the end of the rearward swing of the collating table.

50 One of the features of the present invention is the provision of a pivoted collating table, mounted on the typewriter carriage, with work-sheet holding clips arranged to be operated by movement of said table about its pivot.

55 Another feature is the arrangement for always holding collated work-sheets, either by clips or feed-rolls of the machine, against

slipping in the machine, said clips and feed-rolls being so connected that both cannot be in open or ineffective position at the same time.

Other features and advantages will here- 60 inafter appear.

In the accompanying drawings,

Figure 1 is a side elevation, partly in section, of the carriage and associated parts of the typewriting machine, and the collating 65 device embodying the present invention, and shows the feed-rolls in effective position.

Figure 2 is an end elevation, partly in section, on a reduced scale, of the same, the collating table being shown in position just 70 before the feed-rolls begin to release the work-sheets lying against the platen. The dot-and-dash outlines of the collating table illustrate its extreme forward and rearward positions.

75 Figure 3 is a fragmentary end elevation, partly in section, on a reduced scale, of the same, the collating table being shown in its extreme forward position slightly ahead of its collating position, and the feed-rolls held 80 away from the platen.

Figure 4 is a partial front elevational view, on a reduced scale, of the same.

Figure 5 is a partial top view of the left 85 end of the collating device, and the adjacent portions of the typewriter-carriage on which it is mounted, showing the paper-holding clip in released or open position.

Figure 6 is a top view of the left-hand 90 paper-holding clip of the collating device and adjacent portions of the typewriter-carriage on which it is mounted, showing the clip in closed or effective position.

Figure 7 is an end elevation, partly in section, of the carriage and associated parts of 95 a typewriting machine embodying a second form which the present invention may take, and shows the feed-rolls in effective position.

Figure 8 is a fragmentary end elevation, 100 partly in section, of the same, the collating table being shown in position just before the feed-rolls begin to release the work-sheets lying against the platen. The partial dot-and-dash outline of the collating table illustrates its extreme rearward position.

Figure 9 is a fragmentary end elevation, 105 partly in section, of the same, the collating table being shown in its extreme forward position, and the feed-rolls away from the platen.

Figure 10 is a partial top view of the aforesaid second form of collating device, embodying the present invention, and adjacent parts of the typewriting machine on which it is mounted, the paper-holding clips being shown in released or open positions.

Figure 11 is a top view of the left-hand paper-holding clip, as shown in Figure 10, and also shows adjacent portions of the col-
10 lating device, the clip being shown in closed or effective gripping positions.

Figure 12 is a fragmentary front view of a form the present invention may take, and also illustrates how any of the herein-mentioned paper-holding clips may be made adjustable upwardly and downwardly.

A platen 10, by means of an axle 11, is journaled in side plates 12, as usual in a standard Underwood typewriting machine. The usual rear paper-shelf 13 has apron-extensions 14 for guiding work-pieces around the platen 10 to the printing line at the front thereof. Front and rear feed-rolls 15 and 16 are supported on shafts 17 and 20, the latter seated on arms 18 and 21 of the bell-crank levers pivotally mounted on a shaft 19. The bell-crank levers which comprise the arms 18 and 21 have other arms 22 and 23 which depend to the rear and front, respectively, of a shaft 24 which is journaled in hanger plates 31 supported on shaft 19. Leaf-springs 25, bearing against arms 18 and 21, tend to rock the arms upwardly to force the feed-rolls 15 and 16 against the platen 10, and therefore tend to press the arms 22 and 23 against the shaft 24, which has flats 26 cut thereon at points where the arms 22 and 23 engage the same. Shallow transverse slots 22^a and 23^a may be provided in the arms 22 and 23 at points where the edges of the flats 26 engage the arms when the shaft 24 is revolved. The function of the slots will be explained hereinafter. When the feed-rolls 15 and 16 are in effective positions, the arms 22 and 23 stand slightly free of the flats 26, as shown in Figure 1. When, however, the shaft 24 is revolved sufficiently, the arms 22 and 23 are forced apart and draw down the feed-rolls 15 and 16, as shown in Figure 3. The feed-roll mechanism, except the slots 22^a and 23^a just described, is that found on the standard Underwood typewriting machine.

55 The feed-rolls 15 and 16 may be thrown off and on the platen 10 by swinging the pivoted collating table 42 forwardly and rearwardly about its pivot 45, which may be shoulder-screws fastened to depending arms 44 which extend downwardly from mounting plates 47 fastened on the side plates 12 by screws 48. The feed-rolls 15 and 16 are connected through the following parts to the pivoted collating table 42 mounted on a cross-arm 41. The transverse arm 34 on the right end of shaft 24 is con-

connected to a link 35 which has in its upper end a slot 35^a. A pin 36^a mounted in the lower end of the crank-lever 36 is arranged to work in the slot 35^a. The function of the slot 35^a will be explained hereinafter. The crank-lever 36 is mounted on a rigid stub-shaft 37 supported between the right-hand side plate 12 and a side bracket 38^a. The key-lever 33 is mounted on the outer end of the stub-shaft 37. A short rocking arm 38 is rigidly fastened to the stub-shaft 37. This arm may have an open-ended slot 38^b extending inwardly from the free end thereof, in which may be engaged a rocking pin 39 secured in the right-hand swingable pivoted arm-member 43, which, with a similar left-hand pivoted arm-member 43, supports the cross-arm 41 which carries the table 42.

The work-sheets may be collated on the table 42 which may be composed of similar right and left hand table-sections, each arranged with a pair of lengthwise slots 53 to provide for adjustable lateral mounting on the cross-arm 41 by screws 54, to accommodate different widths of work-sheets. In collating position, the table 42 may be vertical or inclined a small amount to the rear (see Figure 3), and in inoperative position it may be swung out of the way further to the rear (see Figure 1). The collating table 42 is held or latched in its forward or collating position by the friction of the arms 22 and 23 on the edges of the flat portions 26 of the shaft 24 and also by the edges of the flat portions 26 being seated in the slots 22^a and 23^a of the arms 22 and 23 (see Figure 3). These slots may have sloping ends, so that the edges of the flat portions 26 may swing out of them upon a light rearward pressure on the collating table 42. Each of the collating-table sections 42 may have along its outer edge an upturned flange 42^a arranged at right angles to the axis of the platen 10 to serve as side or lateral gages for work-sheets. A small section of each flange 42^a adjacent its lower end may be removed, and, on the sides of the opening caused thereby, may be riveted small right-angle plates 55 and 56, the former having an upwardly-bent finger 57 extending substantially half-way between the angle plates. Clips 60 may be pivotally mounted between the angle plates 55 and 56 on a pin 58 extending between the plates, and held there-

to. A short forwardly-extending tongue 61 120 may project from the hub portion of each clip 60. One end of a small tension-spring 59 is secured to the tongue 61, and the other end to the finger 57 with a small amount of initial tension to cause the clips 60 to normally tend to grip the work-sheets against the table 42, as illustrated in Figure 6. 125

When the collating table 42 is swung rearwardly from a forward position to its rear-most position, the clips 60 are caused to 130

automatically release work-sheets gripped by them by means of the following arrangement of parts. The mounting plates 47 have slotted transverse arms 67 extending inwardly at a short distance back of the furthest rear position of the collating table 42. Stop-members 64 are mounted on the arms 67 by screws 65, and may be laterally adjusted by means of slots 66. The forward rounded ends 64^a of the stop-members 64 may strike against the sloping heel-portions 63 of the pivoted clips 60 and swing its curved end portion 62 into released or open position just as the collating table, being swung backwardly, reaches its furthermost rear position. The paper-clips 60 may be arranged to open right after the feed-rolls 15 and 16 have been thrown against the platen 10 by means of the above-described connection between the table and the feed-roll-release mechanism. When the collating table 42 begins to swing forward from its rearmost position, the clips 60 begin closing immediately, but because of a small ineffective movement of the pin 36^a in the slot 35^a, the feed-rolls 15 and 16 do not begin to move away from the platen 10 until the clips have gripped the work-sheets 91 and 92 against the table 42. By the above-described co-action of the clips 60 and the feed-rolls 15 and 16, work-sheets in the typewriting machine, after once being gripped by the clips 60, cannot slip in the machine by the operative inadvertently moving the collating table.

To provide a rear stop for the collating table 42, short flanges 49 are bent up on the mounting plates 47 in rear of the collating table. The rearwardly-extending stop-members 46 provided on supporting arms 43, are arranged for their rear ends to strike against studs 50, strongly fastened to the flanges 49 when the collating table 42 has been swung to its rearmost position. To hold the collating table 42 in its rearmost position, flexible latch-members 51 having straight portions and substantially V-shaped rear end portions 51^a, are fastened to the back of the cross-arm 41, and are arranged so that the V-shaped ends may hook over the studs 50. A slight pull on the collating table 42 will disengage the latch, and allow the former to swing forward freely. The forward movement of the collating table may be stopped at the right point by the pins 44^a engaging with the stop-members 43^a of the supporting arms 43.

In Figures 7, 8, 9, 10 and 11 are shown views of a collating device embodying the present invention which employs work-sheet-holding clips and associated minor parts different from those described above. The clips 160 may have spoon-shaped inner ends 162, and straight flexible shank portions 167, the outer ends of the same being

fastened by screws 163 to transversely bent mounting portions 149^a of upwardly-extending flange-members 149 of mounting plates 147. Studs 150, securely fastened in the rear portions of the flanges 149, are arranged to strike against the rear edges of the supporting arms 143 to limit the backward movement of the collating table 142. The bent mounting portions 149^a are positioned so that when the collating table 142 is in its rearmost position, the clips 160 are open. The clips are arranged to close and grip the work-sheets 91 and 92 before the feed-rolls 15 and 16 begin to move away from the platen by action of the connecting means described above between the collating table and feed-roll-release lever.

In Figure 12 is shown a form of clip 260 different from the two kinds of clips described above. A means for making clips 260 easily adjustable up and down is also disclosed. The clips 260 comprise curved end portions 262, straight portions 267, and downwardly-bent mounting portions 268, the latter being fastened by screws to substantially channel-shaped members 270 having holes in their arms arranged to make a good sliding fit on round mounting rails 271. The rails 271 may be mounted outside the side gage flange-members 242^a, and parallel thereto, on outwardly-bent arms 272 of the side gages 242^a. The rails may have on the sides farthest from the side gages 242^a narrow lengthwise grooves 273. Small spring-depressed rods 269, extending between the two arms of the channel-members 270 and held in slots 270^a in the arms, may engage in the grooves 273 to hold the channel-members from turning on the rails 271, but allowing them to be slipped up and down along the rails. Coil-springs 275 are arranged around the lower ends of said rails, one end of the springs being fastened to adjacent lower arms 272, and the other ends to elongated collars 276 around the rails 271, secured against movement on the rails by a set-screw 277. The springs 275 may be wound clockwise and arranged with an initial torsion, so that they will cause the clips 260 to normally tend to press against the collating table 242. Finger-portions 278 of the collars 276 may be arranged to extend inwardly on the rails 271 and engage against striking members 279 integrally joined with the mounting plates 247 in such a way that just as the collating table 242 reaches its rearmost position, the rails 271 are rotated counterclockwise a small amount, and the clips 260 mounted on them are swung open.

The clips 260 begin closing upon the first forward swinging movement of the collating table 242, and the same connecting means between the collating table and the feed-roll mechanism, described above, may be employed to delay the opening movement of

the feed-rolls of the typewriter until the clips 260 are entirely closed.

It can be readily seen that the above-described means for adjusting the clips 260 up and down can be employed with the first and second above-described kinds of clips. It will also be understood that more than one clip on one side of the collating table may be employed.

10 The collating device 40 of the present invention may be of special advantage in positioning, in a typewriter, statement and ledger-sheets in cases where entries have already been made on the ledger-sheet. The 15 collating table 42 is held in its forward or collating position with the clips in closed or effective position. The statement-sheet and ledger-sheet, with a carbon-sheet between them having its work-surface next to the ledger-sheet, may be inserted together from the rear of the platen in the usual way. The statement and carbon-sheets may be of the same width, and the former arranged to overlie the latter. The ledger-sheet 92 may be as wide or wider than the statement-sheet 91, and may be laterally gaged against the right-hand flange 42^a of the collating table 42. The statement-sheet may be laterally gaged against the left-hand flange 42^a of the collating table. The two flanges 42^a will preferably be spaced a distance apart greater than the width of the ledger-sheet 92, thereby providing for a narrow width of the latter sheet to be exposed adjacent its right edge. The ledger-sheet may have a dash (not shown) at its extreme right edge in line with its last entry, to facilitate positioning the last entry (which may be hidden by the statement-sheet) to substantially one line-space above the printing line of the platen 10, as indicated by type 90. While the ledger-sheet 92 is being positioned, the right-hand clip 60 may be held open by the operative, and, 45 when the sheet is properly positioned, the clip may be released allowing it to grip the sheet by action of the spring 59. It will be noted (see Figure 4) that the right-hand clip 60 does not grip the statement-sheet 91. In like manner, the statement-sheet 50 may be positioned and clipped. The operative may now by a light push on the upper portion of the collating table 42 at any point lengthwise thereof swing it to its rear-most position. Just before the table is stopped the feed-rolls 15 and 16 will be thrown against the platen, gripping the work-sheets in the usual way, and a short interval later the clips 60 will be opened.

60 It can be seen by those skilled in the art that the above-described collating device may be used in doing work where a record-sheet is employed beneath the usual ledger-sheet. For conveniently holding the record-sheet on the platen 10, a roll 95 may be ar-

ranged, as indicated in Figure 1, by the dot-and-dash outline.

Variations may be resorted to within the scope of the invention, and portions of the improvements may be used without others. 70

Having thus described my invention, I claim:

1. The combination with a typewriting machine having a platen and lower feed-rolls engaging the platen, of a displaceable 75 collating table, a work-sheet-holding clip mounted on said table, and mechanism actuating said feed-rolls and said clip to provide co-operative work-sheet-holding action between the latter and said feed-rolls, whereby one or the other will always hold a collated work-sheet against displacement. 80

2. The combination with a typewriting machine having a carriage, of a collating table displaceably mounted on said carriage, 85 said collating table including a clip and a side gage arranged for co-operatively holding collated work-sheets in typing position, and means for releasing said clip upon rearward movement of said table. 90

3. A collating device for a typewriting machine having a carriage, including a collating table pivotally mounted on said carriage, spring-pressed work-sheet-holding clips mounted at each side of said table, and means for closing and opening said clips upon movement of said table about its pivot forward and backward, respectively. 95

4. A collating device for a typewriting machine having a carriage, including a collating table pivotally mounted on said carriage, a spring-pressed work-sheet-holding clip mounted at each side of said table, and means for holding said clips in open positions when said table is in its rearmost position, whereby said clips may be closed upon a small forward movement of said table about its pivot towards its collating position. 100

5. A collating device for a typewriting machine having a carriage, including a collating table pivotally mounted on said carriage, a spring-pressed work-sheet-holding clip at each side of said table, means for opening and closing said clips upon movement of said table about its pivot, and means for adjusting said clips upwardly and downwardly along said table. 110

6. A collating device for a typewriting machine, including a pivotally mounted collating table, work-sheet-holding clips pivotally mounted at the sides of said table, and opening means for said clips operable upon backward movement of said table about its pivot, said means being adjustable so as to permit opening of said clips at different points in the movement of said table. 120

7. The combination with a typewriting machine having a platen and feed-rolls thereagainst, of a pivotally mounted collating 130

- table, work-sheet-holding clips mounted at the sides of said table, means for pressing said clips open when said table is in its rear-most position, and means connecting said 5 clips with said feed-rolls and arranged so as to prevent said feed-rolls from being in a released or ineffective work-sheet-holding position at the same time said clips are pressed open.
- 10 8. In a typewriting machine, the combination with a carriage, a platen, feed-rolls and a feed-roll release lever, of a collating device mounted on said carriage, said device including a collating table mounted on right and 15 left hand pivoted arm members, work-sheet-holding clips at the sides of said table, and means for opening and closing said clips upon movement of said table about its pivot, said right-hand arm member having a projecting rocking pin, and said release lever having a rocking arm with a slot arranged for engagement with said rocking pin, whereby said feed-rolls may be thrown against or away from said platen by movement of said table about its pivot.
- 20 9. In a typewriting machine, the combination with a carriage, a platen, feed-rolls engaging the platen, and a displaceable collating table on said carriage, of means for 25 always holding collated work-sheets against slipping in said machine, said means including clips at the sides of said table for gripping the collated work-sheets, means for opening and closing said clips upon movement of said table forwardly and rearwardly, and interponents for operating said 30 feed-rolls arranged between the latter and said clips, whereby both said clips and said feed-rolls cannot be in open or released position at the same time.
- 35 10. In a typewriting machine, the combination with a carriage, a platen, feed-rolls engaging the platen, feed-roll actuating mechanism, a feed-roll release lever, and a 40 collating table, of means for always holding collated work-sheets against slipping in said machine, said means including arms pivoted on said carriage and supporting said table, work-sheet-holding clips mounted at the 45 sides of said table, instrumentalities for closing said clips by a small forward movement of said table about its pivot from its rear-most position and opening them upon rearward movement of said table to its rear-most 50 position, a rocking pin in one of said arms, a slotted rocking arm on said release lever arranged to engage with said rocking pin, a connecting pin on the lower end of said release lever, and a link-member having a 55 short lengthwise slot in its upper end, said connecting pin arranged to engage in said slot in said link-member, the lower end of said link-member engaging with the feed-roll mechanism whereby said feed-rolls may 60 be operated by movement of said table about its pivot, the elements of said means coacting to prevent both said clips and said feed-rolls from being in open or released positions at the same time.
- 65 11. In a typewriting machine, the combination with a carriage, a platen, feed-rolls, feed-roll actuating mechanism, a feed-roll release lever, and a pivotally mounted collating table on said carriage, of means for always holding collated work-sheets 70 against slipping in said machine, said means including work-sheet-holding clips mounted at the sides of said table, means to hold said clips in open or released position when said table is in its rearmost position, means to 75 close said clips upon a small forward movement of said table, and a connection between said table and said feed-roll mechanism whereby said feed-rolls are held against said platen when said table is in its rearmost 80 position and are caused to move away from said platen by a forward movement of said table about its pivot after said table has moved a small distance forwardly from its rearmost position, said connection including 85 a rocking pin in said table, a slotted rocking arm fast to said release lever arranged to engage said rocking pin, a pin on the lower end of said release lever, and a link-member having its lower end attached to the feed-roll mechanism of said machine and being provided with a short lengthwise slot in its upper end, said slot arranged to engage around said pin in said release lever to permit a small forward idle movement of said 90 table with respect to said feed-rolls.
- 95 12. The combination with a typewriting machine having a feed-roll release lever and a pivotally mounted collating table, of means for latching said table in collating position, 100 said means including said feed-roll release lever, cams operable by said lever, and depending spring-pressed pivoted arms on each side arranged for being pressed outwardly by said cams against spring-pressure, said 105 arms arranged with transverse grooves for latching engagement with said cams when the latter are revolved, said lever being connected with said table whereby swinging the latter forward about its pivot to collating 110 position causes said cams to revolve into latched engagement with said arms.
- 115 13. In a typewriting machine, the combination with a platen, a platen-frame, and a 120 collating table pivotally mounted on said platen-frame, of means for latching said collating table in its forward position and for unlatching the same, said means including a feed-roll-release lever, a pin in said pivotally-mounted table, a slotted rocking arm on said release lever for engaging said pin whereby movement of said table forwardly actuates said lever, a cam-bearing shaft operably connected with said lever, 125 spring-pressed devices having downwardly- 130

depending arms disposed on each side of said shaft, said arms having notches with sloping ends, and cams on said shaft arranged to press said arms apart upon rotation of said shaft caused by forward movement of said collating table, said cams being arranged to engage in said notches to hold said table against accidental movement, and, upon pushing said table rearwardly, 10 to ride out of said notches readily, because of the sloped ends thereof.

14. A collating device for a typewriting machine, including a collating table pivotally mounted on said machine and having work-sheet-holding clips mounted at its sides, means arranged to make said clips inoperative when said table is swung to its rearmost position about its pivot, and a 15 spring-pressed latch for holding said collating table in its rearmost position.

15. A collating device for a typewriting machine, including a collating table pivotally mounted on said machine and having work-sheet-holding clips mounted at its sides, means arranged to make said clips inoperative when said table is swung to its rearward position about its pivot, a spring-pressed latch for holding said collating table in its rearmost position including a 20 rearwardly-extending flexible strip fast to said table, said strip having a straight portion and a substantially V-shaped end portion, and a laterally positioned pin fast to said device in the rear of said table, the 25 V-shaped end of said flexible strip arranged to be engaged behind said lateral pin by a light rearward push of said collating table and to be disengaged by a light forward pull of said table.

16. A collating device for a typewriting machine, including depending members of said device attached to the carriage of said machine, a collating table pivotally mounted on said depending members, work-sheet-holding clips mounted at the sides of said table, a stop for arresting the rearward movement of said table about the pivots having inwardly-projecting lateral studs fast to said device in the rear of said table, and rearwardly-projecting lugs of said table arranged to engage said lateral studs when said table is swung to its rearmost position, and a latch for holding said table in its rearmost position including rearwardly-projecting flexible strips fast to said table and having substantially V-shaped rear ends arranged to engage over said lateral studs when said table is swung to its rearmost position.

17. A collating device for a typewriting machine, including a pivotally mounted collating table, clips pivotally mounted at the sides of said table having their inner ends arranged to extend over and engage against said table to hold work-sheets thereon, and

clip-releasing members mounted in the rear of said table arranged to engage with said clips for opening or releasing the same upon extreme rearward movement of said table about its pivot.

18. In a typewriting machine, the combination with a platen, a platen-carriage, and lower feed-rolls engaging the platen, of a collating table displaceably mounted on said carriage for moving forwardly and backwardly, and means, including a releasing mechanism for said feed-rolls, to latch said table in its forward position.

19. In a typewriting machine having a platen and a platen-frame, the combination with a collating table pivotally mounted on the ends of said platen-frame, of a work-sheet-holding clip mounted at one side of said table, a spring arranged for maintaining said clip in effective condition for gripping work-sheets against said table, and a stationary stop-piece mounted in the rear of said clip and arranged to abut against it and swing it open upon backward movement of said table.

20. In a typewriting machine, the combination with a platen and a platen-frame, of a collating table including a mounting plate fastened on each of the ends of said platen-frame, a cross-bar having arms pivotally mounted on said plates and extending lengthwise of said platen, two guide-plates arranged with upturned integral flanges and mounted on said cross-bar to be laterally adjustable, a normally-closed spring-pressed clip pivoted outside of each of said flanges on extensions thereof and projecting inwardly to engage against the front surface of the adjacent guide-plate, a laterally disposed pin fast in one of said end plates, a rearwardly-extending lug on one of said pivoted arms arranged to abut against said pin and stop the rearward movement of said collating table, and clip-opening pieces adjustably mounted in the rear of said clips for engaging the latter so as to open them just before said lug strikes said pin.

21. In a typewriting machine, the combination with a platen, a platen-frame and feed-rolls normally disposed against the lower side of said platen, of a paper-table pivotally mounted on the ends of said platen-frame, a spring-pressed work-sheet-holding clip mounted on said table at one side thereof, means for throwing said feed-rolls off the platen upon forward movement of said table from its rearmost position, and a clip-actuating piece mounted behind said clip and arranged for pressing the same open when said paper-table is in its rearmost position, said piece being adjustably mounted whereby said clip may close and grip work-sheets against the forwardly moving table just before said feed-rolls are thrown off said platen.

22. In a typewriting machine, the combination with a platen and a platen-frame, of a collating table displaceably mounted on said platen-frame for moving forwardly and backwardly, a shaft mounted on flanged extensions of said table a short distance beyond one side edge thereof, a clip mounted on said shaft for turning with it and for being adjusted therealong up and down and for extending over the adjacent edge of said table to engage against its surface, a spring engaging said shaft and being arranged with initial tension for turning the same to cause said clip to normally press against said table, and a clip-actuating piece positioned in the rear of said collating table and arranged to rotate said shaft upon backward movement of said collating table to swing said clip off said table. 55
23. In a typewriting machine, the combination with a platen and a platen-frame, of mounting plates fastened on the ends of said platen-frame, a collating table displaceably mounted on said mounting plates for movement forwardly and rearwardly, upturned flanges on said mounting plates adjacent the sides of said table, and a work-sheet-holding clip consisting of a leaf-spring fastened on each of said flanges and extending inwardly therefrom and having a spoon-shaped end-portion arranged for engaging against said table when the latter is moved forward to its collating position, said clip being positioned so as to release work-sheets upon movement of said table to its rearmost position. 60
24. In a typewriting machine, in combination, a platen, a platen-frame, feed-rolls engaging said platen on its lower side, a collating table pivotally mounted on said platen-frame, feed-roll-release mechanism operated by the forward movement of said collating table for throwing said feed-rolls off said platen, and means, including said release mechanism for latching said table in its forward position. 65
25. In a typewriting machine, in combination, a platen, a platen-frame, feed-rolls engaging said platen on its lower side, a collating table displaceably mounted on said
- platen-frame, means operated by movement of said collating table for moving said feed-rolls to and from the platen, and means for latching said table in its extreme forward position. 70
26. In a typewriting machine, the combination with a platen, a platen-frame and lower feed-rolls engaging the platen, of a collating table having downwardly-depend- 65
ing arms pivotally mounted on said platen-frame, a rocking pin on one of said arms, a feed-roll-release lever, a stub shaft fast on said lever, a rocking arm on said shaft having an open slot engaging about said pin, whereby movement forwardly and rearwardly of said table actuates said rocking arm and said lever and moves said feed-rolls away from and against said platen, respectively, and a latch for holding said table in its rearmost position to insure that the feed-rolls are engaged against said platen. 75
27. In a typewriting machine having a platen, lower feed-rolls and upper feed-rolls, the combination with a platen-frame, of a collating table pivotally mounted on said platen-frame, side gages on said table, work-sheet-holding clips at the sides of said table, and means for actuating said clips by movement of said table, the lower end of the table being positioned so that when moved about 80 its pivot it will clear said upper feed-rolls, whereby the latter may be used to hold a record-sheet against said platen and over which record-sheet may be disposed superposed work-pieces to be held in typing 85 position by said clips and said gages. 80
28. In a typewriting machine, the combination with a platen-frame, of a collating table pivotally mounted on the ends of said platen-frame as a unit and including adjustable side gages, laterally-adjustable paper-holding clips mounted on said table at the sides thereof, resilient means for holding said clips closed when said table is in its forward collating position, and laterally-adjustable clip-actuating pieces disposed in the rear of said table for pressing said clips open. 90
